UNITED STATES PATENT OFFICE.

JACOB FELBEL, OF NEW YORK, N. Y., ASSIGNOR TO UNION TYPEWRITER COMPANY, OF JERSEY CITY, NEW JERSEY, A CORPORATION OF NEW JERSEY.

TYPE-WRITING MACHINE.

No. 838,396.

Specification of Letters Patent.

Patented Dec. 11, 1906.

Continuation of application Serial No. 226,935, filed January 5, 1903. This application filed June 30, 1905. Serial No. 267,805.

To all whom it may concern:

Be it known that I, JACOB FELBEL, a citizen of the United States, and a resident of the borough of Manhattan, city of New York, 5 in the county of New York and State of New York, have invented certain new and useful Improvements in Type-Writing Machines, of which the following is a specification.

My invention relates to type-writing machines, and more particularly to type-bar baskets or rests therefor.

The object of my invention is to provide a simple construction of type-bar basket or rest which is capable of greatly reducing the 15 rebound of the type-bars when they strike the basket in their movements back to normal positions, and thereby avoiding the liability of adjacent type-bars conflicting or colliding near the type-bar basket during the 20 rapid operation of the machine.

To the above and other ends, which will hereinafter appear, my invention consists in the features of construction and combinations and arrangements of parts hereinafter 25 described, and particularly pointed out in the appended claims.

In the accompanying drawings, wherein like reference characters indicate corresponding parts in the various views, Figure 1 is a 30 vertical front-to-rear sectional view of one form of type-writing machine embodying my invention. Fig. 2 is a vertical longitudinal sectional view of the basket, the view being taken on the line $z-z$ of Fig. 1 and looking 35 in the direction of the arrow in said figure. Fig. 3 is an enlarged detail fragmentary perspective view of the pad shown in Figs. 1 and 2. Figs. 4 and 6 are like views showing other forms of pads embodying my invention. 40 Fig. 5 shows in perspective other forms of pins which may be employed. Fig. 7 is a plan view of a pad shown in Fig. 6, and Fig. 8 is an enlarged detail fragmentary perspective view of still another form of pad wherein 45 in both felt and leather may be employed in the construction thereof.

The frame 1 of the machine is surmounted by a top plate 2, which supports a suitable carriage (not shown) that is provided with 50 a platen 3, (Diagrammatically illustrated in Fig. 1.)

The key-levers 4 are pivoted on a rod 5 and have the usual finger-keys 6 and restoring-springs 7. Pivots connected to the key-

lever at 8 is a sublever 9, the lower portion of 55 which is slotted at 9^a for coöperation with the fixed fulcrum-rod 10, that extends from side to side of the machine. To the upper end of each sublever is pivoted at 11 a link 12, which is pivoted at its forward end 13 to a type-bar 60 14. To each type-bar is pivoted at 15 a link 16, to which one end of a spring 17 is connected, the other end of said spring being connected to a hook 18, secured to the type-bar basket, designated as a whole by 19. The 65 various type-bars are pivoted on a segmental pivot-wire 20, that is carried by the type-bar segment 21, and the type-bars are adapted to strike upwardly and rearwardly.

The type-bar basket 19 is rigidly supported by rods 22, that extend forwardly from the type-bar segment. Said basket comprises a rigid segmental metallic case or support 23, that is trough-like or U-shaped in cross-section, and this device supports a pad 70 24 throughout or substantially throughout the length thereof. This pad may be made of one piece of felt or other like soft or yielding material or of two pieces of different materials. Extending transversely of the pad and seated or embedded therein edgewise of the pad and at intervals throughout its length are horizontally-disposed parallel pins 25, which are preferably of a non-resilient material, such as copper or lead. In Figs. 1, 2, and 3 80 85 these pins are indicated as separate pieces and are entirely surrounded by the pad, excepting at their ends. From an examination of Fig. 1 it will be observed that the sides of the trough-like support extend up and over 90 the ends of the pins, so as to prevent a longitudinal displacement thereof from the pad.

The pins instead of being separate pieces, as indicated in Figs. 1, 2, and 3, may be connected or made in the form of staples 25^a, as 95 in Figs. 4 and 8, or the pins may be connected one to another throughout the series thereof, as indicated in Figs. 6 and 7, wherein a comb-like piece of copper or other suitable hard or inflexible material is seated or embedded in the pad. The various pins, fingers, or projections 25^b extend laterally from a connecting-bar 25^c, so as to form a comb-like structure. The pins may extend in substantially the same relation to the pad as the 105 separate pins 25 shown in Figs. 1, 2, and 3. The construction shown in Figs. 6 and 7 from certain aspects may be regarded as a

pad having a longitudinally-extending metallic strip seated or embedded therein, the metallic strip having openings or spaces at intervals throughout the length thereof.

5 It should be understood that the pins or pieces may be round or of any other suitable shape or size in the cross-section, two additional forms being shown at 25^a 25^b in Fig. 5.

Instead of making the pad of a single body 10 of felt or like soft material it may be constructed as illustrated in Fig. 8—that is to say, a lower longitudinally-extending strip 26 of leather or other material may be surmounted by a longitudinally-extending strip 15 of felt 27 and the two strips secured together in any suitable manner, as by cement *a* or stitching *b*, with the transverse pins or metallic pieces interposed between them. In the employment of a pad such as just described I prefer to use the felt strip to receive 20 the impact of the type-bars. In any detail construction a felt pad or facing reduces noise to the minimum; but unfortunately it causes an excessive rebound of the type-bars unless some means are specially provided for 25 reducing the same. This I have provided, and my pads yield the minimum of sound and rebound.

It will be observed that the pins or pieces 30 extend in the general directions of the type-bars when the latter are at rest on the pad which normally supports the free ends thereof; that the pins or pieces are fixed within the pad; that certain of them have intermediate connections; that the pins or pieces extend substantially under and crosswise of the upper or contact face of the pad and substantially parallel to said face and that they are arranged transversely of the pad; that 35 the comb-like piece shown in Figs. 6 and 7 extends throughout or substantially throughout the length of the pad and has a portion that extends longitudinally of the pad and integral projections, pins, or fingers that project therefrom transversely of the pad; that the metal pins shown in Fig. 8 are interposed between a plurality of strips of material that extends longitudinally of the pad, and that in the various constructions shown the comb 40 or pins are embedded in the pad within the field of impact of the type-bars against the pad.

The pins or metallic pieces may be inserted while the pad portions are straight, and thereafter the pads may then be given a curvature corresponding to the segmental support 23 provided therefor.

If desired, each pad may be made of several segmental sections butting end to end, 6 though I prefer to make each pad continuous, as shown.

Although I prefer to make the rebound-reducing pins, fingers, or teeth of metal, nevertheless some other equivalent material may 65 be employed instead in so far as the broader

feature of my invention is concerned. These inserted pins or teeth are harder and stiffer than the surface of the pad against which the type-bars strike, and being contained wholly within the pad—that is to say, having no 70 connection with the framing of the machine—they have practically no resiliency and operate to reduce the rebound of the type-bars to an extent such that there is no clashing of adjacent type-bars in the vicinity of the pad 75 when the type-bars are operated rapidly. By using a felt or soft material for the face of the pad there is little or no sound resulting from the impact of the type-bars on their return movements to rest. Hence the desideratum 80 is obtained of a practically noiseless pad with the rebound reduced to a minimum.

What I claim as new, and desire to secure by Letters Patent, is—

1. In a type-writing machine, the combination of type-bars, and a type-bar pad, comprising pieces that extend parallelly in the directions of the type-bars when the latter are at rest and which are embedded in the pad. 85

2. In a type-writing machine, the combination of type-bars, and a type-bar pad comprising embedded pins which are connected one with another by inflexible means, and which are located within the field of impact of the type-bars against the pad. 90

3. In a type-writing machine, the combination of type-bars, a type-bar of resilient material, and pins that are seated immovably within said pad and which are located within the field of impact of the type-bars 95 against the pad.

4. In a type-writing machine, the combination of type-bars, a type-bar pad of resilient material, pins that are seated immovably within said pad and which are located within 100 the field of impact of the type-bars against the pad, and intermediate connections between said pins.

5. In a type-writing machine, the combination of type-bars, and a type-bar basket comprising a pad, and pins that are seated in said pad and are connected one to another and extend in the directions of the type-bars when the latter are at rest. 110

6. In a type-writing machine, the combination of type-bars, and a type-bar pad having substantially parallel pieces seated therein and extending substantially parallel to the type-bars when they are at rest. 115

7. In a type-writing machine, the combination of type-bars, and a type-bar pad having substantially parallel metallic pieces seated therein and extending in the general directions of the type-bars when the latter are at rest. 120

8. In a type-writing machine, the combination of type-bars, a type-bar pad having substantially parallel metallic pieces seated and inclosed therein under and crosswise of the face thereof, and a support for the pad. 125 130

9. In a type-writing machine, the combination of type-bars, a type-bar basket comprising a pad, non-resilient pins seated and fixed within said pad under and crosswise of the face thereof and in the general directions of the type-bars when the latter are at rest, a bar that extends longitudinally of the pad and is connected to said pins, and a rigid support for said pad. 60
10. In a type-writing machine, the combination of type-bars, and a type-bar basket comprising a pad and a fixed comb-like inflexible piece seated and inclosed in said pad within the field of impact of the type-bars against the pad. 15
11. In a type-writing machine, the combination of type-bars, and a type-bar basket comprising a pad of resilient material, and a non-resilient piece seated therein within the field of impact of the type-bars against the pad; said non-resilient piece having a bar portion that extends longitudinally of the pad and projections that extend laterally from said longitudinally-extending portion. 20
12. In a type-writing machine, the combination of type-bars, and a type-bar basket comprising a felt pad, and a non-resilient metallic piece that extends longitudinally of the pad, and has integral pins or fingers that project laterally therefrom and which are seated within the field of impact of the type-bars against the pad. 25
13. In a type-writing machine, the combination of type-bars, and a type-bar basket comprising a felt pad with which the type-bars are adapted to impact and against which they normally rest, a non-resilient metallic piece that extends longitudinally of the pad and substantially throughout the length thereof and has integral laterally-projecting pins or fingers that project therefrom and which are seated in the pad and extend transversely thereof. 35
14. In a type-writing machine, the combination of type-bars, and a type-bar basket comprising a pad that is made up of a plurality of strips, substantially parallel metal pins interposed crosswise between said strips, and means for uniting the strips. 45
15. In a type-writing machine, the combination of type-bars, and a type-bar basket comprising a pad that is made up of a plurality of strips, the strip which receives the impact of the type-bars and against which they normally rest being made of felt, and the base-strip being made of leather, substantially parallel metal pins interposed crosswise between said strips, and means for uniting said strips. 55
16. In a type-writing machine, the combination of type-bars, and a type-bar basket comprising a pad that is made up of a plurality of strips, the strip which receives the impact of the type-bars and against which they normally rest being made of felt, and the base-strip being made of leather, metal pins below the face of the pad and extending transversely of the same, intermediate connections between one pin and another, means for uniting said strips, and a rigid support on which the base-strip bears. 65
17. In a type-writing machine, the combination of type-bars, and a type-bar basket comprising a pad, and a metallic strip that is embedded below the face of said pad and extends longitudinally thereof and has openings or spaces therein at various points throughout its length. 70
18. In a type-writing machine, the combination of type-bars, and a type-bar basket comprising a pad, a series of substantially parallel pins that are seated within said pad and extend transversely thereof within the field of impact of the type-bars against the pad, and a trough-like rest that supports the pad and prevents longitudinal displacement of the pins. 80
19. In a type-writing machine, the combination of type-bars, and a type-bar basket comprising a pad, a series of pins that are seated within said pad and extend transversely thereof, and a substantially U-shaped support for the pad, the side walls of said support extending over the ends of the pins in the pad and preventing displacement of the pins from the pad. 90
20. In a type-writing machine, the combination of type-bars, and a type-bar pad having pieces seated and inclosed therein transversely of the pad and substantially parallel with the impact-surface of the same. 100
21. In a type-writing machine, the combination of type-bars, and a type-bar pad having pieces that are spaced apart longitudinally of the pad and which are inclosed within and extend transversely thereof and which are substantially parallel to the impact-face of the pad. 105

Signed in the borough of Manhattan, city of New York, in the county of New York and State of New York, this 28th day of June, A. D. 1905.

JACOB FELBEL.
